UNITED STATES PATENT OFFICE.

ASEL B. GODFREY, OF CHERRY, NEBRASKA.

AUTOMOBILE ATTACHMENT FOR SELF DRAFT.

Application filed February 14, 1922. Serial No. 536,567.

To all whom it may concern:

Be it known that I, ASEL B. GODFREY, a citizen of the United States, and residing in the county of Cherry, (post-office address 5 Hyannis) Nebraska, have invented a new and useful Automobile Attachment for Self Draft, of which the following is a specification.

This invention relates to a new and useful draft attachment for motor vehicles. The main object of this device is to provide a mechanism for pulling a vehicle out of mud or sandy places by its own power.

Another object is the provision of a pulley for a belt drive for sundry useful tasks about the farm, as pumping water, sawing wood, and grinding corn.

Fig. 1 is a perspective view of the device as applied to an automobile wheel.

Fig. 2 is a cross-section on the line 2—2 of Fig. 1.

Fig. 3 is a cross-section on the line 3—3 of Fig. 2.

Fig. 4 is an end view of the winding drum.

Fig. 5 is a longitudinal section of the square block fitting on the tapered end of the shaft.

Fig. 6 is an elevation of the clasp which holds the cap in position.

The device consists of a winding drum and means to secure it to an automobile shaft and a covering cap, fastened by a clasp.

The vehicle shaft 10 has a section 10^a of diminished size and a squared tapered end portion 11. The hub 16 fits on the diminished cylindrical portion 10^a and is fastened to the wheel W by bolts 19 which also hold the base section of the drum 18. A squared block 13 having a concave head and a beveled square center which latter fits on the squared end 11 is held on the shaft by nut 12. The cable winding drum designated generally as 15 has a hub section 14 with an internal bore of square conformation. The cable is designated C.

The cap or casing consists of two parts held together by a ring and clasp. The base, or portion fastened to the wheel as 50 hereinbefore set forth, is 18, and the outer portion is numbered 17. The ring 21 is split as shown in Fig. 6, and is brought to closed position by the clasp 22, 23. This clasp is of a well-known type and consists of a handle 55 section 22 fastened to ring 21 by the strap 24, to which is attached pivotally a staple shaped link 23. To clasp this ring the end of link 23 is placed in hook 25 fastened to one section of the ring by screws, and the handle 22 moved to the right to close proximity with ring 21 thus pulling together and holding the ends of the ring.

To operate the cable winding device the cap section 17 is removed and drum 15 is 65 slid to outer position till it is released from hub 16 and is held in position on block 13, and one end of the cable taken from the drum, and fastened to any stationary object and the engine of the vehicle started, thus 70 driving the rear axle and winding the cable on the drum, without driving the wheel, thus giving its entire power to the drum. The operation of the belt drive is similar.

The device is simple and strong in construction and easy of manufacture.

What I claim is:

In combination, a round axle with a beveled square end, a square block with a beveled square center to fit the beveled square 80 end of the axle, a hub with a round bore to fit the round part of the axle and square outside, a drum square inside to fit over the square block and the square portion of the hub, a hub cap to fit over the drum, and a 85 clasp for attaching the cap in position.

In testimony whereof I affix my signature in presence of two witnesses.

ASEL B. GODFREY.

In presence of:—

D. F. COGOOD,
WINIFRED EGAN.
